WILLIAM F. TRAUDT, OF BUFFALO, NEW YORK.

APPARATUS FOR CEMENTING SOLES TO SHOE UPPERS.

Application filed December 18, 1926. Serial No. 155,584.

This invention relates to apparatus for cementing soles to the upper leather of shoes and is designed to produce a press structure which can be used for half-soling 5 two shoes at a time, and for whole-soling or half soling a single shoe with equal facility. To this end the apparatus consists essentially of a proper pad of generally rectangular shape, one or two presses movable 10 lengthwise over said pad and means for preventing the bulging upward of that portion of the pad not acted on by one of the presses if the other is not being used. The best forms of apparatus at present known 15 to me embodying my invention are illustrated in the accompanying three sheets of drawings in which:

Fig. 1 is a side elevation of a machine for operating on high heeled shoes. 20 Fig. 2 is a similar view of a modification adapted to half-sole either high heeled or flat heeled shoes, and shown half-soling one of the latter.

Fig. 3 is a similar view showing the 25 operation of whole soling.

Fig. 4 is an end elevation of Fig. 3.

Fig. 5 is a side elevation showing another modification.

Fig. 6 is a vertical section on line 6—6 of 30 Fig. 5, and

Figs. 7 and 7^a are perspective views of one type of apparatus.

Fig. 8 shows a modified form of retarding plate.

Throughout the drawings like reference 35 characters indicate like parts. 1 represents generally the bed of the machine which has a downwardly bent portion 1^a adapted to receive and retain a small quantity of fluid such as glycerine, water or air, when the depression formed by it is covered and enclosed by fluid-tight diaphragm 2 of rubber generally covered by a facing of leather 2^a as shown in Fig. 6. This diaphragm is held

40 down on the bed of the machine and forms an airtight joint therewith through the agency of the clamping frame 3 which is bolted to the bed as shown in Fig. 6. An outlet cock 4, and an inlet connection 5, each controlled by a valve, are shown in Figs. 3, 4 and 5, by manipulation of which the quantity of fluid confined beneath the diaphragm 2 can be controlled. The parts 45 so far described cooperate to form a fluid supported pad which is the preferred form

of pad element employed in my invention although in some cases pads of other construction might be substituted.

The pad so formed is preferably generally rectangular in outline and the sides of the bed sustaining it are provided with longitudinally extending ribs 6 on which slide one or more press housings 7, 7^a by means of grooved feet 8, 8^a engaging said ribs. 9, 9^a represent generally screws mounted in said 55 press housings and adapted to force downward specially constructed lasts 18, 18^a which fit inside of shoes 19, 19^a or 20, which are to be half soled or whole soled as the 60 occasion may require.

When the operator is half-soling, two 65 shoes may be operated on at once as shown in Fig. 1 by means of the two presses there shown. If whole-soling is to be done only one shoe can be operated on at a time as 70 shown at 20 in Fig. 3, one of the presses then being removed and the other one moved over into mid-position on the bed 1.

It is evident that in the half-soling operation only a portion of the pad is covered by 75 one shoe and that, if the pad is of the liquid supported variety, the uncovered portion of the diaphragm will bulge upward under the fluid pressure, and that time will be wasted in forcing down the shoe (as 19) any additional distance to take up the play in the diaphragm thus permitted before the necessary degree of resisting pressure is 80 encountered for the cementing operation. Also this excessive depression of the one 85 shoe may produce such a distortion of the diaphragm that the operation will not be entirely successful. The use of another press in which the other shoe 19^a can be 90 operated on at the same time overcomes this difficulty, each shoe acting as a retarding device to prevent the bulging up of the diaphragm which would otherwise be produced by the pressure of the other shoe.

In some cases the operator may desire to 95 half-sole a single shoe and in that case I substitute for the other shoe and its press a special diaphragm retaining device which may be of the form shown in Fig. 2, comprising a smaller housing 12 in which the screw and hand wheel 11—22 are mounted to press upon a plate such as 10 shown in Figs. 6 and 7. This plate has a thicker, reinforced portion 10^a on which the screw 11 bears. The screw 11 renders the retarding 100

device adjustable, but in cases where this is not necessary a non-adjustable housing 13 may be employed as shown in Figs. 5 and 6. The rigid support afforded by a housing such as shown at 13 is also advantageous in some cases because it prevents the retarding plate from tipping.

The retarding device may be adjustably connected to the press housing 7 by the threaded rods 14 and nuts 15 as shown in Figs. 5 and 6 so that it will move with the press housing 7 and be automatically pushed to the left out of operation when the press is moved to the middle position for whole-soling. This is indicated in dotted lines in Fig. 5. In all cases the housings 12 or 13 slide along the ribs 6.

At least one end of the bed 2 should be raised as shown at 16 in Fig. 2 to support high heeled shoes in half-soling. A retarding plate shaped to hook over such a raised end is shown at 23 in Fig. 8. The other end 17 may be shaped to cooperate with flat heeled shoes as shown in Figs. 2 and 5. If 25 the operator has enough work to keep two presses going, each may have a bed shaped at each end to support high heeled shoes in one case, and flat heeled shoes in the other case. Thus in Fig. 1, the two bed ends 16 and 16^a are both shaped to support high heeled shoes for half-soling while in Figs. 2, 3, 5 and 7, one end of the bed is for high-heeled shoes and the other for flat heeled shoes. The screw 11 on the diaphragm retaining apparatus may be simply used for adjustment thereof, having a knurled head 21 as shown in Fig. 7^a, or it may be used for operating the press in place of the screw 9 if it is given a hand wheel 22 as shown 40 in Fig. 2 or other means by which a considerable degree of pressure can be applied to the fluid supported pad through the plate 10. In this mode of use the screw 9 in the main press bearing on the last 18 will be 45 adjusted for operating on shoes having soles of a given thickness and then the hand wheel screw 11—22 will be backed off to permit the shoe and last to be inserted in position and then said hand wheel will be revolved and 50 plate 10 forced down to create the necessary pressure under the shoe. After the cementing has been completed, the hand wheel screw 11—22 will be backed off again for 55 releasing the shoe and last so they can be removed and new ones inserted and the operation again repeated. In the same way in operating the double press structure of Fig. 1 it is usually necessary to operate only one of the press screws 9 or 9^a, the withdrawal of pressure from the fluid under the diaphragm permitting both shoes to be removed. Other forms of lasts may be substituted for the special forms shown in the drawings.

Among the advantages of the invention

may be mentioned the flexibility of use in enabling a machine with one press to be used either for half soling or whole soling, the increase of output rendered possible by the use of the double press structure, the 70 convertibility of the apparatus for use in half soling either high heel or flat heeled shoes, and the speed and accuracy of work possible in half soling resulting from the use of the device for preventing upward 75 bulging of the unused portion of the dia-phragm surface.

Having described my invention I claim:

1. In an apparatus for cementing soles to shoes having a pad and a press for forcing a shoe down on said pad surface, the combination, with the above recited elements, of a laterally sliding connection between said pad structure and said press; whereby the latter may be used for whole-soling when in mid position over the pad, or for half-soling when in either end position.

2. A combination such as defined in claim 1 in which said pad is shaped to fit a high-heeled shoe at one end and to fit a low-heeled shoe at the other end.

3. In an apparatus for cementing soles to shoes the combination of a fluid supported pad long enough for whole-soling a shoe, a press which is movable lengthwise of said pad and adapted for forcing a shoe against it, means adapted to rest on a portion of said pad not covered by the shoe and so prevent it bulging upward, and a detachable apparatus adjusting the position of said means longitudinally of said pad.

4. A combination such as defined in claim 3 in which said last mentioned means comprises a screw press movable over said pad.

5. A combination such as defined in claim 3 in which said means for preventing the upward bulging of the pad comprises a second shoe press.

6. In an apparatus for cementing soles to shoes the combination of a bed, a liquid supported diaphragm mounted on said bed of generally rectangular shape, guide ribs extending along either side of said bed, and two presses for shoes, each mounted on said bed and having feet engaging said ribs and capable of sliding along the same, whereby two shoes may be half-soled at the same time, or one press removed and the other moved into mid-position and used for whole soling.

7. In an apparatus for cementing soles to shoes, the combination of a liquid supported pad of generally rectangular surface, a screw press adapted to operate on a shoe and its contained last, which press is movably mounted over said pad and adapted to slide lengthwise of the same, and means adapted to prevent upward bulging of portions of the pad surface not covered by the

shoe, said means being also movable longitudinally of said pad and connected to said screw press so as to move with it.

8. A combination such as defined in claim 7 in which said means and said press are connected by screw threaded members whereby their distance apart may be adjusted.

9. In an apparatus for cementing soles to shoes, having a fluid supported pad long enough for whole-soling a shoe, the combina-

tion, with said apparatus, of means adjustable so as to force all or part of a shoe sole against said pad, whereby either whole-soling or half-soling may be effected, and 15 removable restraining means adapted to rest on any portion of said pad not covered by the shoe in half-soling and to thereby prevent the portion of the pad so covered by said removable means from bulging upward 20 during a half-soling operation.

WILLI M F. TRAUDT.
